SPECIFICATION forming part of Design No. 15,158, dated July 22, 1884.

Application filed May 29, 1884. Term of patent 7 years.

To all whom it may concern:

Be it known that I, WILLIAM H. COLEMAN, a citizen of the United States, residing at New Orleans, in the parish of Orleans and State of Louisiana, have invented and produced a new and original Design for a Box, of which the following is a specification, reference being had to the accompanying drawing, forming part thereof.

10 The drawing is a perspective view of my newly-designed box, which is made to represent a bale of cotton in miniature.

The cotton is represented exposed at A, the bagging at B, the hoops or bands at C, and the

buckles or "ties" at D. At E are represented the lacing stitches to hold the edges of sack-ing at the ends of the bale. The body of the box is shown at F and the lid at G, the line of separation being at H H.

I claim—

The design for a box herein shown and described, the same consisting of a body and lid representing a cotton-bale in miniature.

WILL. H. COLEMAN.
